Claims priority, application Germany Apr. 3, 1958

3 Claims. (Cl. 281—19)

Assembly folders of synthetic material for storing cases made of synthetic material or for showing of so-called prospectus cases made of transparent soft foil are known; these folders have many different kinds of devices for filing, which devices are made entirely of metal in the form of screw springs, wire bows, etc. and which need fittings, again of metal and composed of several parts, for the connection to the folder.

Many and real disadvantages arise for the assembly folders through these metal holding devices.

First of all such filing devices demand a comparatively great amount of space, in height and in width, so that such folders have to have a wide, unhandy back which for the most part is not fully utilized and which absolutely is not necessary. The closed and only partly filled folder then forms a long wedge which makes it impossible to stack many folders. In addition, the folder takes up correspondingly more space on a shelf, etc. Moreover, the single assembly folders are already somewhat bulky due to the broader back necessary for the fittings, etc. so that there is not, or not sufficient, room left in a dispatch case for other articles or these must be pressed together in a disadvantageous manner. Furthermore these metal holding devices increase the weight of the folder and it is not only the metal itself but also the thick-walled, stiff folder cover, necessary for fastening the fittings, which contribute to the weight. If the folder consists of thin walls and flexible parts as for example in a paper folder, then only filing tongues can be used, not devices of the mentioned type.

Furthermore assembly folders of the letter file type are known which have a filing device placed on a track on the inside of the folder back and which track can be inserted and removed.

The invention relates to an assembly folder of synthetic material especially for cases made of synthetic material which produces a new type of assembly folder, an intermediate type between the stiff folder and the paper folder and which avoids the drawbacks of these two types.

The invention consists therein that an inside strip arranged on the folder back has a bent-in fold on its free edge which, together with the turning fold of the inside strip, compose the guide for the track.

This design has a number of advantages.

First of all, the assembly folder remains flat because there are no filing members and thus the wide back also must be used since the flat inside strip is used as a guide and the stack of cases filed on the track lies between said track and the rear folder cover. The reduced weight of the assembly folder is also important; this is accomplished through the light weight execution of the folder as well as by not using any metal parts. The dependable and permanent embedding of the case stack by means of the track is especially to be noted; this is enclosed by the inside strip so that a loosening of this binding or an independent loosening or falling out of the track with its filed stack of cases is impossible, whereby it makes no difference whether the assembly folder is kept in a standing or hanging position. Finally the simple method of use is important: the track, filled with the stack of cases is inserted into the inside strip from one end of the same, either from the bottom or from the top, or conversely, removed, in order to be able to exchange the cases on the track in the usual manner.

2

The following embodiments show the object of the invention:

FIG. 1 is a perspective view,

FIG. 2 is a front elevation, enlarged,

FIG. 3 is a view from above, and

FIG. 4 shows a detail.

The assembly folder consists of the rear cover 1 and the front cover 2 which are of hard foil and of conventional synthetic material.

The inside narrow and elongated strip 3 is arranged on the folder back and is made advantageously of one piece with the rear folder cover 1, which, according to the invention, is shaped to form the guide for the track 4, which serves to carry the stack of the filed cases.

15 This guide is, compare FIG. 2, formed by an inwardly bent fold or lip 6 on the free edge of the inside strip 3 and by the turning fold 7 of the strip 3, so that a U-shaped setting is formed which holds the track 4 securely and in spite of this makes it possible to insert 20 or remove the track easily.

It is possible to provide a second fold independent of this on the inside of the fold 7, which can be made in one piece with the inside strip 3; also the fold or lip 6 (or in some cases both folds) can run somewhat bent 25 against the strip 3 whereby the fold receives a certain amount of spring which increases the clasping ability without any disadvantageous influences on the changeability.

The track 4 is provided with a holding device for the 30 cases 5 to be filed, which holding device can in general be shaped in different ways. In most cases the usual flexible filing tongues 8 are sufficient; they are shown as dotted lines in FIG. 3. These tongues have the advantage that they lie flat on the track 4 again so that the filed 35 cases 5 and the bent over tongues can be inserted into or removed from the U-shaped inside strip 3 without any difficulty. The filed case stack 5 on the track 4 makes it easier to introduce and to remove the track 4 into, respectively, out of, the U-shaped inside strip 3, in that the stack 5 for example is held directly next to the track with the thumb and first finger and then, while introducing the track is either pulled upward, or, when being removed, pulled downward, so that only one movement is necessary to lay the track 4 free so that the cases can be exchanged.

In order to insert the track 4 into the U-shaped inside strip 3 it is appropriate to cover the holding device, i.e. the filing tongues or prongs 8, or some other equipment arranged for this purpose, with an auxiliary strip 9, see 50 FIG. 4. This auxiliary strip can also be made of synthetic foil whose upper half is connected, either glued or welded, with the track 4 and whose lower half loosely covers the filing tongues 8 so that these can be laid free when they are to be used.

55 The attention is also drawn to the fact that there is taken a special measure which serves to increase the holding capacity considerably. It is advantageous when the cases 5 are executed with a simple foil appendage 10 arranged on the filing end and which is equipped with perforations. The appendage consists thus of a simple thin foil so that even when 30 or more cases are stacked there is still a comparatively thin package which can be easily put between the inner strip 3 and the rear cover 1 without too much expansion of the folder taking place.

60 The rear cover 1 is connected advantageously with the front cover 2 by a back strip 11 composed of soft foil. It must be said, however, that the execution of the assembly folder as such can be formed as wished, i.e. so that the rear cover 1 with the front cover 2, together with the back strip 11 and the inside strip 3 all consist of one piece of foil, whereby the inside strip 3 for ex-

ample is formed by a fold. In the same manner the foil for the rear as well as for the front cover can be chosen as to the type of synthetic material, as to strength or as to transparency or opaqueness.

I claim:

1. An assembly folder for storing thin transparent soft foil cases, letterhead sheets and the like comprising a cover of relatively stiff flat sheet material, said cover having a narrow elongated strip integrally formed therewith, folded inwardly from the inner edge of the cover sheet to overlie the same, and extending substantially the full length thereof providing an integral relatively rigid guide, said elongated strip lying in fixed parallel plane relationship with the inner face of the cover sheet, an inwardly folded guide and retaining lip integrally formed on the elongated strip to oppose the integral fold of the elongated strip upon the cover sheet, said guide lip extending parallel to and slightly spaced from the underface of the elongated strip, an elongated track of relatively stiff flat sheet material slidably mounted in the rigid guide and under the guide lip of the elongated strip between the opposing lip and the fold of the narrow elongated strip upon the cover and retained against longitudinal displacement within the rigid guide by the clasping action of the lip, and a holding device carried by said track for releasably securing the thin cases, letterhead sheets and the like to the track.

2. An assembly cover for storing thin transparent soft foil cases, letterhead sheets and the like as defined in claim 1, and said holding device running along one face of the track and having bendable and releasable prongs extending through the track and adapted to extend through the thin soft foil cases, letterhead sheets and the like and bent over and longitudinally extended along the

5
10

opposite face of said track to lie flush against the cases, letterheads and the like to releasably retain them upon the track, a soft flexible foil member surrounding both faces of said flat elongated track and secured to the one face thereof to retain the bendable prong holding device against outward displacement from the one face thereof, said soft flexible foil being folded over one edge of the track and extending inwardly to loosely cover the soft foil cases, letterheads and the releasably longitudinally extended prongs whereby to facilitate the longitudinal sliding of the track within the rigid guide without interference of the prong holding device upon the track with the cases, letterheads and the like being assembled upon or disassembled from the rigid guide and cover sheet.

15
20
25

3. An assembly folder for storing thin transparent soft foil cases, letterhead sheets as defined in claim 1, and a second cover of similar relatively stiff flat sheet material disposed along the inner side edge of the first mentioned cover, and a flexible foil hinge strip secured flush upon the outer face of the narrow elongated strip of the first mentioned cover and secured flush upon the faces of the second cover along the inner edge thereof.
